UNITED STATES PATENT OFFICE

OLCOTT HASKELL, OF SAUSALITO, CALIFORNIA

TOOL-HANDLE

Application filed September 22, 1931. Serial No. 564,341.

My invention relates to the class of tool-handles adapted for ready application to and removal from the tool-shank as occasion may arise.

One object of the invention is to provide a handle of this type which by reason of its shape, together with its positional relation to the tool, affords a comfortable grip of great firmness and leverage.

Another object, in the complete development of the invention, is to provide such a handle adapted for application of any of a number of tools, as each may be needed, to the end that a single handle may severally serve a plurality of tools according to the shape of their shanks. To attain these objects the handle herein comprises a disk having a diameter adapting it for convenient and firm grasp in the palm of the hand, and a thickness sufficient for the formation of a plurality of shank-receiving sockets in its periphery, each socket having such shape as adapts it for a firm grip upon the shank of the particular tool intended for it.

In the accompanying drawings I have illustrated the handle in its preferred form, though it will be understood that changes may be made in details of construction and manufacture, without departing from the spirit of the invention as defined in the claims hereunto appended.

In the drawings, Fig. 1 is a front elevation of the handle, showing, in dotted lines, a boring bit fitted to it.

Fig. 2 is a section of the handle on the line 2—2 of Fig. 1.

Fig. 3 is an edge view of the handle, looking from the line 3—3 of Fig. 1.

1 is a disk constituting the handle having a flattened central portion terminating in a rounded laterally projecting periphery which enables the handle to be firmly grasped and turned. It may be made of any suitable material, and may have a unitary structure, or be composed of sections. For manufacturing and marketable considerations it is deemed preferable to make it, as indicated in Fig. 3, of symmetrical complementary halves, stamped out of metal, and butt-welded to form a hollow body or shelf, light

in weight and of ample rigidity. Its diameter, as hereinbefore mentioned is such as to adapt it for a convenient manual grasp, and its thickness is such as will enable it to be provided with the shank-receiving sockets in its periphery, each socket having a proper depth and cross-section to hold with a firm, but readily detachable grip the shank of any tool adapted to fit therein.

For example, there is a tapering socket 2, round or angular and of relatively small diameter, for receiving the correspondingly shaped shanks of files or screw drivers; a tapering slot or mortise 3 to hold the flat shank of a file; a tapered square-section socket 4 for all kinds of boring bits, such as are used in a brace; or, finally, suitable sockets for any other of various tools for the shanks of which the sockets are adapted.

In Fig. 1 I have indicated in dotted lines a boring bit 5, the shank 6 of which is fitted in the socket 4. From this figure, it will be seen that the tool projects radially from the disk, so that the latter is edgewise aligned with the tool and not at right angles to it as are the hand-wheels of cocks or faucets; and though, in respect to its alignment with the tool, it has a function of the ordinary handles of such tools, yet by reason of its disk-shape it has all the leverage of a wheel and in addition it is capable of a more effective grasp, and of receiving severally a plurality of tools.

In using this handle, it is only necessary to have it within convenient reach or in the pocket; then select from the rack the particular tool wanted; and then fit the tool shank in the proper socket in the perimeter of the disk. When the use of this tool is complete, withdraw it, replace it in the rack, select another tool, and fit it to its socket in the handle. Thus the same handle is readily adaptable for separate use with a plurality of tools, and is of special advantage with such tools or bits as are adapted for use in a brace.

In order to adapt this disk-handle for additional use, as, for example, a temporary substitute for the intentionally removed hand-wheel of a hydrant; there is provided through the axis of the disk a socket 7 for fitting upon

the top of the rotatable stem of the hydrant valve.

As best seen in Fig. 2 the sides of the complementary disk parts comprising the tool handle may be formed with internal recesses 8 in line with each other within which the shank of the tool may fit after insertion through the lower recess 4.

I claim:—

- 10 1. A universal tool handle comprising a disk having a flattened central portion terminating in a rounded laterally projecting continuous periphery provided with spaced radial apertures of varying sizes and configurations for engaging the corresponding shanks of different tools.
- 20 2. A universal tool handle comprising a hollow disk having a dished central portion terminating in a rounded laterally projecting continuous periphery provided with spaced radial apertures of varying sizes and configurations for engaging the shanks of various tools, said disk consisting of a pair of complementary cup-shaped members joined together.
- 30 3. A tool handle consisting of a hollow disk formed of complementary parts and having a peripheral aperture adapted to receive the shank of a tool and having the opposite sides of the disk formed with internal recesses 8 in line with said apertures within which said shank may fit.

In testimony whereof I have signed my name to this specification.
